VOICE SILENCER

Louis S. Scher, New York, N. Y.

Application May 21, 1940, Serial No. 336,345

12 Claims. (Cl. 181—34)

The present invention relates to voice mufflers or silencers for the "hand set" type of telephones for muffling the voice of a speaker desiring to converse confidentially in the presence of others.

This invention is an improvement over my previous structures patented November 12, 1935 and October 4, 1938, and bearing the respective numbers 2,020,970 and 2,131,820, and is designed to overcome some of the faults of these structures and those of the prior art.

The present structure is neat, trim, inexpensive to produce, and is further characterized by the ease with which it may be disassembled for thorough cleaning and sterilization.

Seeking to provide a muffler of practical and efficient form, the invention contemplates the provision of a body having removable association with the mouthpiece of a telephone instrument and fitted with a preferably swingable mouth engaging portion which may be swung to a position within the body to clear the telephone support when the instrument is placed thereon and which may be swung outwardly of the body when in use.

The invention also contemplates the provision of novel sound absorbing means disposed within the muffler body and deals with the structure of said means.

The muffler further incorporates novel features of construction tending to provide a compact and efficient device for the purpose intended.

The foregoing and many other objects, features and advantages will be hereinafter set forth or will become apparent as this disclosure progresses. The features of the invention have been incorporated in the device as illustrated in the accompanying drawing and the following specification is based thereon.

In the drawing:

Fig. 1 is a front view of a portion of a "hand set" type of telephone fitted with a muffler designed in accordance with the invention.

Fig. 2 illustrates a telephone mouthpiece with the muffler in longitudinal section and ready for use.

Fig. 3 is a top plan view of one portion of the body of the muffler.

Fig. 4 is a bottom plan view thereof.

Fig. 5 is a plan view of a sound absorbing unit used in the muffler.

Referring now to the illustrated embodiment of the invention, a telephone support is shown at 5, said support being provided with a base 6. In the usual manner, the support cradles a "hand set" instrument 7 provided with a transmitter or mouthpiece 8. As can be seen from Fig. 1, a

portion of the transmitter has vertical overstanding relation with the base 6 when the "hand set" instrument is cradled on the support and that only a small amount of clearance is provided between the transmitter and said base and the surface upon which the telephone rests. It is evident then, that the muffler must be of such design as to clear such parts if undesirable shifting thereof into and out of operating position is to be obviated.

To this end, the muffler body 9 preferably comprises a transmitter engaging member 10 removably fitted with a preferably domed mouthpiece supporting member 11, the latter supporting a swingable mouthpiece 12. These members 10, 11, and 12 are preferably moulded of hard rubber, Bakelite, or other such materials and are substantially rigid and non-deformable.

The member 10 is preferably formed with an opening 13 in which the transmitter 8 is engaged, a seat 14 being provided to limit the position of the transmitter within the opening 13. In order to removably hold the member 10 on the transmitter, means may be provided, such as the retaining springs 15 carried by the member 10, for engaging the transmitter and gripping the same.

The body member 10 is preferably circular in contour with the opening 13 eccentrically disposed to provide a widened portion which in this instance is hollow to form the crescent shaped trough 16. The bottom of said trough is preferably lined with a sound absorbing element 17 of felt or the like.

The member 10, on its lower face, may be provided with a rabbet 18 formed by said face and a rib 19 to receive the upper edge portion of the mouthpiece supporting member 11. Suitable means may be provided to give detachable association between the members 10 and 11. The latter member, which is formed as substantially half of a hollow sphere, is preferably provided with an angularly disposed opening 20 in substantial register with the opening of the transmitter 8. In this opening is positioned the mouthpiece 12.

The mouthpiece 12 is preferably formed as a curved tubular member having a rim 21 and provided with a lug 22 which is seated against the underface of the member 10, said lug being confined against displacement by a portion of the member 11. The lug 22 is so positioned in its seat as to become a hinge point for the mouthpiece 12 which may thus be swung from the retracted position of Fig. 1 to the "in use" position of Fig. 2, the former condition being neces-

sary to obviate interference with both the base 6 and the surface on which the telephone is supported when the transmitter instrument is on its support.

The muffing of the sound being directed into the mouthpiece 12 is accomplished primarily by a sound absorbing unit 23 disposed within the body 9. As at present conceived this unit comprises the felt portions 24 and 25 each curved in two transverse planes so that they are shaped as portions of hollow spheres or substantially so. The felt portion 24 reasonably follows that part of the body member 11 adjacent which it is disposed, its edge being seated upon lugs 26 formed in the body member 10 and within the trough 16. The felt portion 25 has its edge seated against a lug 26^a in said trough and is eccentrically arranged with respect to the portion 24 so that its opposite edge meets and follows the commensurate edge of said portion 24.

In the above manner, an extension 27 of the trough 16 is formed between the felt portions 24 and 25 leaving a felt-lined chamber into which the transmitter 8 opens and into which the mouthpiece may be swung when out of use.

Inasmuch as a feature of the invention is the ease with which the parts of the muffler may be disassembled for thorough cleaning, it is essential that said parts can be easily handled. While the sound-absorbing unit 23 may be formed to give the desired rigidity for handling, it is preferred to set the edges thereof into light channels 29 to obviate the collapse or derangement of said edges and to indent the walls of said channels, as at 30, to pinch the felt members 24 and 25 to prevent inadvertent separation of the channels from said felt members.

To permit free circulation of air in the chamber 28 and to prevent "blasting," the member 10 may be provided with the holes 31 communicating said chamber with atmosphere when the mouthpiece 12 is covered during use.

In use, the instrument 7 is removed from its support and the mouthpiece swung outwardly to the position shown in Fig. 2. The mouth is pressed against the rim 21 to prevent escape of sound being directed to the transmitter 8. The sound circulates in the chamber 28 and for the most part is absorbed by the felt member 25. Such sound as penetrates this member finds its way into the troughs 16 and 27 to be absorbed by the felt members 17 and 24. By this time, any sound which finds its way out of the muffler is so indistinct as to be unintelligible.

From the foregoing it is evident that an improved and novel voice muffler has been provided in a preferred form of embodiment. It is further apparent that changes in designs, incorporating the principles and features of the invention, may well be made without departing from the spirit and scope of the appended claims.

I claim:

1. A voice muffler comprising a hollow body formed of two separable members, sound absorbing means carried by one of said members, and a rigid mouthpiece carried by the other of said members, said mouthpiece being retractable within said other member.

2. A voice muffler comprising a two-part body, one of said parts being adapted for engaging association with a telephone transmitter, sound absorbing means carried by said body part, the other of said parts being carried by the first mentioned part and provided with an angularly disposed opening, and a mouthpiece of substan-

tially non-deformable material, swingably mounted on said second part and within said opening for ready retraction within, and extension out of said other part.

3. A voice muffler comprising a two-part body, one of said parts being adapted for engaging association with a telephone transmitter, and formed with a crescent-shaped trough, sound absorbing material disposed in said trough, a sound absorbing unit carried by said part and extending beyond said trough and having a chamber communicating with said trough, the other of said parts being carried by the first-mentioned part and formed with an opening, and a mouthpiece of substantially non-deformable material, swingably mounted on said second part for ready retraction within, and extension out of said second part through said opening.

4. A voice muffler for a telephone transmitter comprising a transmitter-engaging member having an opening into which the transmitter of a telephone instrument is snugly though removably fitted, and having a seat against which the transmitter rests, said member being substantially circular with the said opening being eccentrically disposed relative thereto to provide a hollow crescent-shaped trough, a sound-absorbing lining in the bottom of said trough, a mouthpiece-supporting member removably fitted to the transmitter-engaging member and being formed as a hollow, substantially hemispherical element and having an angularly disposed opening to register substantially with the opening in the transmitter, a mouthpiece formed as a curved tubular member having an annular rim, and a hinge lug on said mouthpiece in interfitting pivotal engagement with the said supporting member.

5. A voice muffler for a telephone transmitter comprising a transmitter-engaging member having an opening into which the transmitter of a telephone instrument is snugly though removably fitted, and having a seat against which the transmitter rests, said member being substantially circular with the said opening being eccentrically disposed relative thereto to provide a hollow crescent-shaped trough, a sound-absorbing lining in the bottom of said trough, a mouthpiece-supporting member removably fitted to the transmitter-engaging member and being formed as a hollow, substantially hemispherical element and having an angularly disposed opening to register substantially with the opening in the transmitter, and a mouthpiece having pivotal engagement with said mouthpiece-supporting member and swingable in relation thereto.

6. A voice muffler for a telephone transmitter comprising a transmitter-engaging member having an opening into which the transmitter of a telephone instrument is snugly though removably fitted, and having a seat against which the transmitter rests, said member being substantially circular with the said opening being eccentrically disposed relative thereto to provide a hollow crescent-shaped trough, a sound-absorbing lining in the bottom of said trough, a mouthpiece-supporting member removably fitted to the transmitter-engaging member and being formed as a hollow, substantially hemispherical element and having an angularly disposed opening to register substantially with the opening in the transmitter, and a mouthpiece disposed in said opening and being pivotally mounted for swingable movement from a position within the mouthpiece-supporting member to a position protruding therefrom.

7. A voice muffler for a telephone transmitter comprising a transmitter-engaging member having an opening into which the transmitter of a telephone instrument is snugly though removably fitted, and having a seat against which the transmitter rests, said member being substantially circular with the said opening being eccentrically disposed relative thereto to provide a hollow crescent-shaped trough, a sound-absorbing lining in the bottom of said trough, a mouthpiece-supporting member removably fitted to the transmitter-engaging member and being formed as a hollow, substantially hemispherical element and having an angularly disposed opening to register substantially with the opening in the transmitter, and a mouthpiece having pivotal engagement with said mouthpiece-supporting member and swingable in relation thereto, a sound-absorbing unit disposed within the mouthpiece-supporting member, said unit comprising two walls of fibrous material each curved in transverse planes to produce shapes substantially as portions of hollow spheres, one of said walls reasonably following the adjacent wall of the mouthpiece-supporting member with one edge supported on lugs in the trough of the transmitter-engaging member, the other fibrous wall being seated on lugs in the opposite wall of said trough and eccentrically disposed relative to the first wall so that the outer edges of both said walls meet and merge together, the said two fibrous walls constituting in effect a continuation of the trough walls.

8. A voice muffler for a telephone transmitter comprising a transmitter-engaging member having an opening into which the transmitter of a telephone instrument is snugly though removably fitted, and having a seat against which the transmitter rests, said member being substantially circular with the said opening being eccentrically disposed relative thereto to provide a hollow crescent-shaped trough, a sound-absorbing lining in the bottom of said trough, a mouthpiece-supporting member removably fitted to the transmitter-engaging member and being formed as a hollow, substantially hemispherical element and having an angularly disposed opening to register substantially with the opening in the transmitter, and a mouthpiece having pivotal engagement with said mouthpiece-supporting member and swingable in relation thereto, a sound-absorbing unit disposed within the mouthpiece-supporting member, said unit comprising two walls of fibrous material each curved in transverse planes to produce shapes substantially as portions of hollow spheres, one of said walls reasonably following the adjacent wall of the mouthpiece-supporting member with one edge supported on lugs in the trough of the transmitter-engaging member, the other fibrous wall being seated on lugs in the opposite wall of said trough and eccentrically disposed relative to the first wall so that the outer edges of both said walls meet and merge together, the said two fibrous walls constituting in effect a continuation of the trough walls, said mouthpiece being retractable into the supporting member and withdrawable therefrom.

9. A voice muffler for a telephone transmitter comprising a transmitter-engaging member having an opening into which the transmitter of a telephone instrument is snugly though removably fitted, and having a seat against which the transmitter rests, said member being substantially circular with the said opening being eccen-

trically disposed relative thereto to provide a hollow crescent-shaped trough, a sound-absorbing lining in the bottom of said trough, a mouthpiece member removably fitted to the transmitter-engaging member and being formed as a hollow, substantially hemispherical element and having an angularly disposed opening to register substantially with the opening in the transmitter.

10. A voice muffler for a telephone transmitter comprising a transmitter-engaging member having an opening into which the transmitter of a telephone instrument is snugly though removably fitted, and having a seat against which the transmitter rests, said member being substantially circular with the said opening being eccentrically disposed relative thereto to provide a hollow crescent-shaped trough, a sound-absorbing lining in the bottom of said trough, a mouthpiece member removably fitted to the transmitter-engaging member and being formed as a hollow, substantially hemispherical element and having an angularly disposed opening to register substantially with the opening in the transmitter, a sound-absorbing unit disposed within the mouthpiece member, said unit comprising two walls of fibrous material each curved in transverse planes to produce shapes substantially as portions of hollow spheres, one of said walls reasonably following the adjacent walls of the mouthpiece member with one edge supported on lugs in the trough of the transmitter member, the other fibrous wall being seated on lugs in the opposite wall of said trough and eccentrically disposed relative to the first wall so that the outer edges of both said walls meet and merge together, the said two fibrous walls constituting in effect a continuation of the trough walls.

11. A voice muffler for a telephone transmitter comprising a transmitter member, said member being substantially circular with an opening being eccentrically disposed relative thereto to provide a hollow crescent-shaped trough, a sound-absorbing lining in the bottom of said trough, a mouthpiece member removably fitted to the transmitter member and being formed as a hollow, substantially hemispherical element and having an angularly disposed opening to register substantially with the opening in the transmitter member.

12. A voice muffler for a telephone transmitter comprising a transmitter member, said member being substantially circular with an opening being eccentrically disposed relative thereto to provide a hollow crescent-shaped trough, a sound-absorbing lining in the bottom of said trough, a mouthpiece member removably fitted to the transmitter member and being formed as a hollow, substantially hemispherical element and having an angularly disposed opening to register substantially with the opening in the transmitter member, a sound-absorbing unit comprising two walls of fibrous material each curved in transverse planes to produce shapes substantially as portions of hollow spheres, one of said walls reasonably following the adjacent wall of the mouthpiece member with one edge supported on lugs in the trough of the transmitter member, the other fibrous wall being seated on lugs in the opposite wall of said trough and eccentrically disposed relative to the first wall so that the outer edges of both said walls meet and merge together, the said two fibrous walls constituting in effect a continuation of the trough walls.
